Primary Examiner — Wendy L Arminio*Assistant Examiner* — Maheen Khurshid(74) Attorney, Agent, or Firm — Eunyoung Lee(57) CLAIM

The ornamental design for a mask with a cat shaped embellishment, as shown and described.

DESCRIPTION

FIG. 1 is a perspective view of a mask with a cat shaped embellishment of the present invention;

FIG. 2 is a front view of FIG. 1.

FIG. 3 is a back view of FIG. 1.

FIG. 4 is a left side view of FIG. 1.

FIG. 5 is a top view of FIG. 1; and,

FIG. 6 is a bottom view of FIG. 1.

The broken lines in the drawings depict portions of the mask with a cat shaped embellishment that form no part of the claimed design.

1 Claim, 6 Drawing Sheets
